UNITED STATES PATENT OFFICE.

WALTER C. WALLIS, OF HOPE, ARKANSAS.

TRANSPORTATION DEVICE.

1,232,414.

Specification of Letters Patent. Patented July 3, 1917.

Application filed June 29, 1915. Serial No. 37,067.

To all whom it may concern:

Be it known that I, WALTER C. WALLIS, a citizen of the United States, residing at Hope, in the county of Hempstead and State 5 of Arkansas, have invented new and useful Improvements in Transportation Devices, of which the following is a specification.

This invention relates to transportation devices, the object in view being to produce 10 a rolling carrier for merchandise in general, which may be operated either by animal or mechanical power, the container being in the form of a hollow cylinder to which access may be had for introducing and removing 15 the merchandise, said container also operating as an efficient road roller, thereby not only preventing injury to the road surface but in reality improving said road surface in a manner similar to the ordinary road 20 roller now in common use.

A further object of the invention is to provide novel driving mechanism for the transportation device, whereby the latter may be driven by engine power, in a simple 25 and direct manner without any possibility of injuring the road surface due to the presence of the driving mechanism.

A further object of the invention is to provide in connection with a plurality of 30 hollow cylindrical containers, a frame in which said containers are journaled, and means for permitting one of the containers 35 to turn relatively to an adjacent container in order that the device as a whole may be steered either when operated by animal or mechanical power.

With the above and other objects in view, the invention consists in the novel construction, combination and arrangement of parts, 40 as herein described, illustrated and claimed.

In the accompanying drawings:

Figure 1 is a side elevation of a transportation device embodying the present invention, the same being shown as equipped with 45 an engine for driving the same.

Fig. 2 is a plan view thereof.

Fig. 3 is a vertical longitudinal section taken about in line with one of the flexible driving elements.

Fig. 4 is a side elevation omitting the engine and showing the device equipped with a draft animal appliance.

Fig. 5 is an end elevation of one container showing the same reticulated and provided 55 with a door.

Fig. 6 is a side elevation showing a larger

number of containers coupled together by a common frame in which they are journaled.

In the preferred embodiment of this invention, the transportation device comprises 60 a plurality of hollow cylindrical containers 1 and 2 and as indicated in Fig. 6, one or more additional containers 3 may be provided in accordance with the desire of the manufacturer and the particular use to 65 which the device is to be put in practice.

The cylindrical containers 1 are provided with doors 4 either in the cylindrical wall thereof or in one or both ends or heads thereof as indicated in the drawings. Each 70 of the containers is also provided with end journals 5 which are received in journal boxes 6 and 7 in the substantially parallel side bars 8 of a truck frame, the latter being shown as embodying in addition to the side 75 bars 8, a cross member or platform 9 upon which is mounted an engine of any preferred description, said engine being designated generally at A.

In the preferred embodiment of the invention, each of the containers 1 and 2 is provided adjacent to the center thereof with an annular depression 10 containing sprocket teeth 11 around which passes one of a plurality of sprocket chains 12, said 85 chains passing around sprocket wheels 13 on the engine shaft 14. The depressions 10 enable the chains to operate within the outer or peripheral surface of the cylindrical containers, thereby preventing any possibility 90 of injuring the road surface over which the device is being drawn or propelled. In some cases it may be necessary to drive only one of the cylindrical containers while in other cases the driving means may extend to one 95 or more additional containers as indicated in the drawings.

In addition to the engine and the container driving means hereinabove described, a draft appliance designated generally at B 100 may be employed, the same being shown for convenience as comprising the draft pole or tongue 15 and the attaching bars 16 which are connected to the front journal boxes 6 hereinabove referred to. In order to permit the device to be readily steered or turned, the boxes 6 are shown as mounted for fore and aft movement in slots or guide ways 17 in the side bars 8 of the frame so that in view of the fact that the bars 16 of 110 the draft mechanism are attached to said boxes 6, the forward container will be turned

at an angle in accordance with the direction followed by the draft animal or animals, the depression 10 in the forward container preventing the sprocket chain from jumping off the teeth engaged thereby. It will be understood that instead of sprocket wheels and chains, pulleys and belts or gears may be employed for driving the device.

The transportation device hereinabove described may be propelled or drawn along a road surface with less friction and resistance than an ordinary wagon or truck carrying the same load for the reason that the cylindrical containers have a broad extended surface and cannot sink into the road surface as in the case of ordinary truck wheels. Furthermore, the cylindrical containers act as road rollers and tend to improve rather than injure the road surface over which they pass.

Having thus described my invention, I claim:—

1. A transportation device comprising a pair of hollow cylindrical containers arranged one in advance of the other and having their axes normally parallel, a frame in which said containers are journaled, an engine mounted on said frame, driving means connecting said engine with one of said

containers, the frame comprising substantially horizontal side bars formed with longitudinal slots, journal boxes slidable in said slots, and container end journals working in said boxes, whereby the axes of the containers may be thrown out of parallel relation to each other for steering purposes.

2. A transportation device comprising a pair of hollow cylindrical containers arranged one in advance of the other and having their axes normally parallel, a frame in which said containers are journaled, an engine mounted on said frame, driving means connecting said engine with one of said containers, the frame comprising substantially horizontal side bars formed with longitudinal slots, journal boxes slidable in said slots, container end journals working in said boxes, whereby the axes of the containers may be thrown out of parallel relation to each other for steering purposes, and yieldable means in front and rear of said journal boxes for centering the same.

In testimony whereof I affix my signature in presence of two witnesses.

WALTER C. WALLIS
